UNITED STATES PATENT OFFICE.

SOLOMON H. DWIGHT AND WILLIAM B. CHAMBERS, OF DECATUR, ILL.

IMPROVEMENT IN WHEELED CULTIVATORS.

Specification forming part of Letters Patent No. 101,240, dated March 29, 1870.

To all whom it may concern:

Be it known that we, SOLOMON H. DWIGHT and WILLIAM B. CHAMBERS, of Decatur, in the county of Macon and State of Illinois, have invented certain new and useful Improvements in Wheeled Cultivators; and we do hereby declare the following to be a full, clear, and exact description of the construction and operation of the same, reference being had to the accompanying drawings, making a part of this specification, in which—

Figure 1 represents a perspective view of the cultivator, and Fig. 2 represents a longitudinal vertical section taken through the same.

Similar letters of reference, where they occur in the separate figures, denote like parts in both of the figures.

Our invention relates to the particular construction of the bolstered truck supported in and carried by a pair of wheels, and the manner of arranging and uniting therewith the pair of independent cultivators, as will be explained, with the hinged guards annexed thereto.

To enable those skilled in the art to make and use our invention, we will proceed to describe the same in connection with the drawings.

The truck or carriage frame is supported in a pair of wheels, A A, and is constructed substantially as follows: The journals a a, just inside of the heels of the hubs of the wheels that they respectively carry, are bent upward, as shown at b b, and flanged or recessed to receive the bent-up ends c c of the short horizontal bars d d, which, from their being at or near the line or plane of the journals, might be termed "short axles." The bars d d are adjustable on the bent ends of the journals, so as to raise the truck or carriage frame thereon, or to lower it, as the case may be, and thus raise or lower the points of the cultivator-beams attached to said bars, as will be hereinafter explained.

At or near each end, respectively, of the pair of bars d d, there are arranged bolsters e e' e', which support upon their elevated ends a quadrangular frame, f f f f, to which the tongue g and tongue-braces g' are attached, and by which the machine is drawn and guided. The cultivator-beams B B are connected, respectively, to the bars d d at the points i i, and may be set to or from each other by means of adjustable holes in said bars, and suitable

uniting-irons, which allow said beams to move freely, not only horizontally but vertically and independent of each other. The joints at i allow of the horizontal and those at j j of the vertical movements of the said beams. The standards C, that carry the cultivator-teeth or plows D, are placed fore and aft on opposite sides of their respective beams, and are braced, as at h, to said beams. The teeth or plows are fastened to the standards by a plate-ring and key. (Shown at 1 2 3 on the drawings.)

At or near the front end of each of the beams B B there is pivoted an angularly-bent and downwardly-inclined drag-bar, k, each of which carries a guard of thin metal, E, which is set edgewise, and rounded or made of a runner form at its front, the rear ends of said guards being united to the standard by a chain, m, and hook n, so that they may be raised or lowered at pleasure. These guards run between the plows and the plants, and guard the latter from injury from or by the former. Each beam B has a single handle, F, attached to it and braced, as at O, so that the two make a pair of handles, which the operator, who walks behind the machine, holds in his hands, and by which he guides and directs the teeth or plows along the rows of plants.

Projecting from the rear of the frame f there are two horns, p p, upon each one of which one of the beams can be thrown up, caught, and carried, as seen in Fig. 2, when the cultivator is being transported from field to field or from place to place.

The elevated frame f admits of the cultivation of plants that are very tall without interfering with or injuring them.

Having thus fully described our invention, what we claim therein as new, and desire to secure by Letters Patent, is—

In combination with an elevated truck-frame constructed and arranged as described, and supported and carried upon a pair of wheels, as herein stated, the pivoted beams B B, and the cultivator-teeth or plows, and independently-pivoted and suspended guards E, connected therewith, and arranged to be drawn by or carried on said elevated frame, as described.

S. H. DWIGHT.
W. B. CHAMBERS.
